UNITED STATES PATENT OFFICE.

LUTHER L. HIGBY, OF FORT WORTH, TEXAS.

DESIGN FOR AN ADVERTISING-BANNER.

SPECIFICATION forming part of Design No. 20,241, dated October 28, 1890.

Application filed September 12, 1890. Serial No. 364,791. Term of patent 14 years.

To all whom it may concern:

Be it known that I, LUTHER L. HIGBY, a citizen of the United States, residing at Fort Worth, in the county of Tarrant and State of Texas, have invented and produced a new and original Design for Advertising or Display Banners; and I do hereby declare the following to be a full, clear, and exact description of the same, reference being had to the accompanying drawings, forming a part thereof.

Figure 1 is a view of my banner, and Fig. 2 a view of same showing different means for suspending it.

The feature of my design consists in an advertising or display banner having thereupon surface ornamentation and lines, as herein-after described.

In the drawings, A designates the banner, of any suitable material, which has upon one of its surfaces horizontal and vertical lines forming spaces, as D E F, as shown, and in which spaces is designed to be printed any

suitable advertising or display matter. Entirely surrounding said spaces D E F and near the edges of the banner and conforming to the shape thereof is a fancy border consisting of a sinuous line G to give a finish to the banner. Bangles are suspended from the lower edge of the banner, and means, such as shown, are provided for suspending the latter.

What I claim is--

The design for an advertising or display banner herein shown and described, the same comprising the strip A, having thereupon the lines forming spaces D E F, and the sinuous line G, entirely surrounding said spaces and conforming to the shape of the strip, as set forth.

In testimony whereof I affix my signature in presence of two witnesses.

LUTHER L. HIGBY.
